(57) CLAIM

The ornamental design for a display screen with icon, as shown and described.

DESCRIPTION

FIG. 1 is a front view of a display screen with icon showing our new design;

FIG. 2 is a front view of the display screen with icon of FIG. 1 with a region for enlargement indicated by broken-line indicia; and,

FIG. 3 is an enlarged view of FIG. 2.

1 Claim, 3 Drawing Sheets
